WELL BIT PROTECTOR

Thomas E. McMahan, Long Beach, Calif.

Application May 5, 1941, Serial No. 391,848

11 Claims. (Cl. 255—1)

This invention relates to well drilling tools and has particular reference to protectors for the bits employed in the rotary method of well drilling. A general object of the invention is to provide a practical, effective and inexpensive protector for well bits.

In the drilling of deep wells with the rotary method it is a common practice to employ roller rock bits. These bits embody toothed roller cutters supported at the lower end of the bit body to independently rotate through contact with the earth formation as the bit is rotated and fed downwardly. It is essential that the cutters be free to rotate and the speed of operation or efficiency of the bit is greatly impaired if the teeth of the cutters become clogged with mud and cuttings. In running a bit down through the well to its operative position the exposed roller cutters accumulate mud and "ball up" and the mud gathers in the valleys between the cutter teeth. The mud or solid matter is scraped from the wall of the well bore as the bit descends and is picked up or accumulated from the column of mud laden fluid standing in the well. In many cases the bit is "balled up" by the time it reaches the bottom of the well bore and is thus made inefficient before it goes into operation.

An important object of this invention is to provide a protector for a well bit which prevents the bit from accumulating mud, cuttings and other solid matter as it is run into the well.

Another object of this invention is to provide a well bit protector which is effective in preventing the cutting parts of the bit from accumulating mud from the well fluid and in preventing the cutting parts from gouging, scraping or cutting mud and earth formation from the wall of the well as the bit is being run into the well. The protector of the present invention not only shields the cutters against the mud laden fluid in the well but also prevents the cutters from gouging, scraping and cutting the well wall, thus preventing injury to the mud layer on the well wall.

Another object of this invention is to provide a bit protector of the character referred to that permits the free passage of fluid between the cutters and body legs and into or through the well string so that it does not interfere with the free lowering of the bit through the well.

Another object of this invention is to provide a well bit protector of the character referred to that is extremely simple and inexpen-

sive to manufacture and that is readily shipped and transported.

Another object of the invention is to provide a bit protector of the character mentioned that is easily and quickly applied to the bit when the same is to be run into the well.

A further object of this invention is to provide a bit protector that is quickly drilled up, when the drilling operations are begun, to be reduced to small fragments that are readily carried to the ground surface with the circulation fluid.

The various objects and features of my invention will be fully understood from the following detailed description of typical preferred forms and applications of my invention, throughout which description reference is made to the accompanying drawing, in which:

Fig. 1 is a side elevation of a typical roller rock bit equipped with one form of protector of the invention. Fig. 2 is a plan view of the protector shown in Fig. 1 in a flat or stretched out condition with broken lines illustrating the positions of the bit cutters. Fig. 3 is a view similar to Fig. 2 showing another form of protector of the invention arranged on the bit, and Fig. 4 is a fragmentary elevation stretch-out view of the under side of the protector shown in Fig. 3.

The protectors of the present invention may be designed for use on the various forms and types of well drilling tools. In the following detailed description I will describe typical embodiments of the invention as employed on conventional roller rock bits. It is to be understood that the invention is not to be construed as limited or restricted to the specific forms or applications of the invention herein described.

The typical roller rock bit illustrated in the drawing has a body 10 provided at its upper end with a pin 11 for facilitating the attachment of the bit with a drill collar 12 or other part of the rotary well drilling string. The bit body 10 is provided at its lower end with downwardly projecting legs 13 and 14. Outer roller cutters 15 are rotatably supported at the inner sides of two diametrically opposite legs 13. The cutters 15 are supported to have downwardly and inwardly sloping axes of rotation and to project downwardly and outwardly beyond the lower ends of the legs 13 to cut the well bore to gauge. The bit further includes cross cutters or inner cutters 16 rotatable about a general horizontal axis and supported between the legs 14 which are spaced about 90° from the legs 13. The cutters 15 and 16 have the usual teeth 17

for acting on the earth formation at the bottom of the well bore and the body 10 has the usual circulation passage 18 and discharge ports.

The protector of the invention illustrated in Figs. 1 and 2 may be said to comprise, generally, a flexible body 20 to be engaged against the lower side of the bit, tabs or straps 21 on the body 20 adapted to be trained upwardly over the exposed toothed side parts of the outer cutters 15, and means 22 for cooperating with the straps 21 to secure the protector to the bit.

The protector body 10 is designed to engage upwardly against and shield the exposed or projecting lower parts of the cutters 15 and 16 and in practice may be designed to cover substantially the entire lower side of the bit. In accordance with the invention the body 20 is formed of a flexible, pliable and readily shaped material to be easily draped or trained over the bit and to generally conform to the cutters 15 and 16. The invention contemplates the formation of the protector body 20 of various materials and contemplates the construction of the body of any inexpensive readily obtained and produced material that possesses the required flexibility and that may be readily drilled up by the bit. The protector body 20 may be formed of fabric, rubber, rubber composition, synthetic rubber, flexible plastic, or the like, or combinations of such materials. I may prefer to form the body 20 of undercured rubber with or without fabric as such material has the desired characteristics of flexibility, strength and low specific gravity and is readily broken up or ground up into small fragments by the bit. The material of which the body 20 is formed preferably has a specific gravity comparable to or less than the specific gravity of the well fluid so that its particles or fragments will be readily carried from the well by the well fluid when the bit is put into operation.

The protector body 20 is preferably, though not necessarily, in sheet form and may be a relatively thin member having upper and lower surfaces occupying parallel planes. The shape of the sheet-like body 20, of course, depends upon the type of bit on which it is to be used. In the case illustrated the body 10 has two diametrically opposite edge portions or edges 23 curved outwardly to substantially conform to the outer active edges of the cutters 15 when the protector is trained over the bit. As illustrated in Fig. 1 of the drawing these edges 23 lie within the cutting range or circumference of the cutter 15 and occur at the outermost active edge parts of the cutter teeth 17 so that the body serves to prevent the teeth from engaging the wall of the well and from accumulating mud as the bit is run down the well. The other edge portions of the body 20 may be formed to merge with the straps 21, as illustrated.

In accordance with the invention the body 20 of the protector is porous, perforated or ported to permit the flow of fluid through the passage 18 when the tool is run into the well. Those portions of the body 20 which lie under the channels or spaces occurring between the spaced adjacent legs 13 and 14 are porous, perforated or ported to provide for the required flow of fluid to and from the passage 18. In the simple preferred construction illustrated the protector body 20 has spaced ports 25 of substantial capacity located to communicate with the spaces or channels occurring between the adjacent legs 13 and

14. The ports 25 are proportioned and arranged to allow the free flow of fluid upwardly past the bit and through the passage 18 when the bit is being run down through the well.

5 The straps 21 are employed to retain the protector in position on the bit and serve to shield or protect the exposed toothed portions of the bit cutters that are above the plane occupied by the body 20. The number and location of 10 the straps 21 may vary with protectors intended for use on different styles and types of bits. In 15 the particular application of the invention illustrated there are four straps 21 extending from the body 20. In the embodiment of the invention being described the straps 21 are integral with the body 20 being continuous extensions of the body. With this construction the complete 20 protector may be readily cut from a sheet of the selected material or stock. As above described, the margins or edges of the body 20 may merge with the edges of the straps 21. With this formation the inner or lower portions of the straps 21 are of increased width, as best shown in Fig. 2. The major upper portions of the straps 21 may 25 have straight generally parallel edges. The straps 21 are of sufficient length to extend upwardly to the shank or drill collar 12 of the bit.

In accordance with the invention the straps 21 are located to extend upwardly around or 30 over the toothed portions of the cutters 15 which are exposed at the sides of the bit and the lower portions of the straps 21 are of sufficient width to fully and effectively shield these portions of the cutters and to close or cover the slots or 35 spaces between the legs 13 and 14. This is clearly illustrated in Fig. 1 of the drawing where it will be seen that the straps 21 engage upwardly around the cutters 15 to fully cover their toothed parts and extend across or cover the gaps between the cutters 15 and the legs 14. Further, it will be observed that the portions of the body 20 at the bases of the straps 21 also curve upwardly at the lower end of the bit to better protect the cutters 15.

40 The means for attaching the protector to the well bit may be varied greatly without departing from the broader aspects of the invention. In the simple case illustrated the means 22 comprises a length of cord, wire 26, or the like, 45 wrapped or trained about the upper portion of the bit or the drill collar 12 thereof and engaged with the straps 21. I have shown slots 27 formed in the upper parts of the straps 21 and have shown the wire 26 threaded through the 50 slots to have dependable engagement with the straps. The ends of the wire 26 are tied or twisted together as at 28.

55 It is believed that it will be apparent how the protector in Figs. 1 and 2 of the drawing may be easily and quickly secured in its operative position on the bit. The body 20 is merely engaged against the under side of the bit with its edges 23 in the correct relation to the cutters 15 whereupon the straps 21 are trained upwardly over the 60 cutters 15 to bring their upper parts to the shank or drill collar 12. The wire 26 is then trained about the shank or drill collar 12 and tied or 65 twisted together at 28. It is preferred to secure the protector so that the body 20 and the straps 21 are tightly drawn on the bit to closely hug and conform to its cutters 15 and 16 and other parts. The protector may be applied to the bit 70 immediately before running the bit into the well. When the bit is lowered through the well the body 20 and the straps 21 cover and shield the

otherwise exposed toothed portions of the cutters 15 and 16 and the gaps between the legs 13 and 14 so that they cannot accumulate mud. The body 20 and straps 21 also serve to prevent the cutters from scraping, gouging or cutting into the side wall of the well bore and thus prevent the cutters from being clogged with the mud layer or earth formation from the well wall. The ports 25 permit the free upward flow of fluid into the passage 18 so that the 10 protector does not obstruct the lower end of the drilling string. When the bit reaches the bottom of the well it is put into operation in the usual way. The toothed cutters 15 and 16 quickly drill up the protector, the protector being cut or reduced to small fragments. These fragments are carried away by the circulation fluid and do not interfere with the drilling operation. The cutters 15 and 16 reach the lower end of the well in a clean condition to operate at their greatest 20 efficiency.

The form of the invention illustrated in Figs. 3 and 4 of the drawing may be said to comprise, generally, a body 20^a, straps 21^a on the body and means 22^a for securing the protector to the bit.

In the structure illustrated in Figs. 3 and 4 the body 20^a and the straps 21^a are separately formed members. The body 20^a may be a generally flat plate or disc-like part formed of a readily drillable material. The body 20^a may be constructed of rubber, rubber composition, synthetic rubber, fabric or a combination of such materials or may be constructed of Bakelite, plastic, or the like. It may be preferred to construct the body 20^a of laminated material whose laminations are readily separated and broken up when the bit is put into operation. It is preferred to construct the body 20^a of a material having a specific gravity comparable to or less than that of the well fluid. The body 20^a may possess substantial flexibility to conform to the cutters 15 and 16 or may be fairly rigid. In the drawing the body 20^a is shown flat when engaged against the bit, it being understood that the body may be sufficiently flexible to be bent upwardly around the cutters 15 and 16 when the protector is operatively secured to the bit. The protector body 20^a is shaped and proportioned to fully cover the under sides of the cutters 15 and 16. In the particular case illustrated the body 20^a has curved edges 30 formed and positioned to lie flush with or to conform to the outermost active edges of the cutters 16. As shown in Fig. 3 of the drawing these edges 30 occur at the lower ends of the cutters 15 and follow the outermost cutting edges of the cutters but do not project beyond the cutters. The body 20^a may have straight edges 31 at the outer ends of the inner cutters 16. The protector body 20^a is porous, perforated or ported to provide for a controlled or directed circulation of fluid through the protector. I have shown four spaced ports 32 formed in the body 20^a and located to register with the gaps or passages between the legs 13 and 14 of the bit.

It may be desired to roughen, corrugate or tooth the protector body 20^a to assure the ready drilling up of the protector by the bit and to prevent the protector from spinning in the well when the bit is put into operation. In the construction illustrated there are corrugations or ridges 33 formed on the upper side of the body 20^a and positioned for engagement by the teeth of the cutters 15 and 16. The corrugations or ridges 33 prevent the cutters from slipping or skidding over the surface of the protector body 75

when the bit is operated to drill up the protector. The under side of the body 20^a may likewise be ridged to have non-rotatable cooperation with the earth formation to the bottom of the well. In the case illustrated, however, the under side of the body 20^a is provided with a central diametric ridge or blade 34. The engagement of the blade 34 with the earth formation effectively prevents the protector from sliding or skidding when the bit is operated to drill up the protector.

The straps 21^a serve the same function as the above described straps 21 being operable to protect or shield the otherwise exposed parts of the cutters 15, to close the otherwise open sides of the spaces between the bit legs 13 and 14, and to assist in securing the protector on the bit. The inner or lower ends of the straps 21^a are suitably fixed to the edge portions of the body 20^a. The straps 21^a may be riveted, pinned, cemented, vulcanized or stitched to the body 20^a depending upon the nature of the materials of which the body and straps are constructed. The straps 21^a may be formed of any selected flexible material that is drillable and that will readily flush from the well. For example, the straps 21^a may be formed of fabric, rubber, rubber composition, or combinations of such materials. The lower portion of the straps 21^a may be thickened 30 as at 35 to better shield the toothed parts of the cutters 15 which extend laterally beyond the legs 13. The straps 21^a are sufficiently long to engage upwardly around the cutters 15 and the upper portion of the bit body 10 to have their 35 upper ends at the bit shank or drill collar 12.

The means 22^a may be the same as the means 22 described above and may consist of a flexible element, such as a cord or wire 36, wrapped about the bit shank and passed through slots 37 in the straps 21^a. The ends of the wire 36 are tied or twisted together to dependably secure the protector on the bit.

The use and operation of the protector illustrated in Figs. 3 and 4 are the same as in the previously described form of the invention. The protector is applied to the bit before running the same into the well and is positioned so that its body 20^a and straps 21^a fully shield the exposed parts of the cutters 15 and 16. The straps 21^a further serve to seal or close the spaces between the legs 13 and 14. When the tool is lowered through the well the protector prevents the exposed toothed parts of the cutter from gathering or accumulating mud and effectively prevents the teeth of the cutters from gouging or scraping the wall of the well. When the bit has reached the bottom of the well it is put into operation. The protector is quickly drilled up or reduced to small fragments which are carried away by the circulation fluid. The ridges 33 and the blade 34 assure the quick drilling up of the body 20^a.

The present invention provides well bit protectors that are very inexpensive to manufacture and that are easily and quickly applied to the bits. The protectors are formed to be readily shipped and transported without danger of breakage and may be employed on practically all forms of well bits.

Having described typical preferred forms and applications of my invention, I do not wish to be limited or restricted to the specific details herein set forth, but wish to reserve to myself any variations or modifications that may appear to those skilled in the art or fall within the scope of the following claims.

Having described my invention, I claim:

1. A protector for a well bit having toothed cutters, the protector comprising a flexible drillable body for covering the cutters, and means for securing the body to the bit.

2. A protector for a well bit having toothed cutters with exposed parts, the protector comprising a flexible drillable body for covering the under sides of said parts, and means for securing the body to the bit.

3. A protector for a well bit having toothed cutters with exposed parts, the protector comprising a drillable body for shielding the under sides of said parts, and straps extending upwardly from the body and trained over the sides of said parts to shield the same.

4. A protector for a well bit having toothed cutters with exposed parts, the protector comprising a drillable body for shielding the under sides of said parts, flexible straps on the body adapted to be trained over the sides of said parts to shield the same, and means cooperating with straps for securing the protector to the bit.

5. A protector for a well bit having roller cutters at its lower end, the protector comprising a flexible body to be engaged under the bit cover and shield the lower parts of the cutters, and flexible parts extending upwardly from the body to be trained over the side parts of the cutters to shield the same.

6. A protector for a well bit having roller cutters at its lower end, the protector comprising a flexible body to be engaged under the bit cover and shield the lower parts of the cutters, and flexible strap-like parts integral with the body and adapted to be trained upwardly over the side parts of the cutters to shield the same and to close the spaces between the cutters.

7. A protector for a well bit having roller cutters at its lower end, the protector comprising a flexible body to be engaged under the bit cover and shield the lower parts of the cutters, the body having a fluid port, flexible strap-like parts on the body adapted to be trained upwardly over the side parts of the cutters to shield the same, and means engaged with the strap-like parts for securing the protector to the bit.

8. A protector for a well bit having spaced cutters on its lower end, the protector comprising a sheet-like body of flexible drillable material shaped to conform generally to the contour of the lower end of the bit and its cutters and adapted to be arranged against the lower side of the bit to shield the cutters, the body having at least one port for communicating with the space between the cutters.

10 9. A protector for a well bit having spaced cutters on its lower end, the protector comprising a sheet-like body of flexible drillable material shaped to conform generally to the contour of the lower end of the bit and its cutter and to lie entirely within the cutting gauge of the cutters, and straps integral with the body to be trained upwardly over the sides of certain of the cutters to shield the same.

20 10. A protector for a well bit having roller cutters on its lower end, the protector comprising a drillable body adapted to be engaged against the lower side of the bit and having its margin shaped to conform generally to the contour of the periphery of the bit and its cutters, a part on the under side of the body for engaging the bottom of the well to hold the body against turning, and means for securing the protector to the bit comprising flexible straps on the body to be trained upwardly over the side portions of the cutters, and securing means for engaging with the straps.

25 11. A protector for a well bit having roller cutters on its lower end, the protector comprising a drillable body adapted to be engaged against the lower side of the bit and having its margin shaped to conform generally to the contour of the periphery of the bit and its cutters, the body having at least one port for passing fluid through the bit, a part on the under side of the body for engaging the bottom of the well to hold the body against turning, and means for securing the protector to the bit comprising flexible straps on the body to be trained upwardly over the side portions of the cutters, and securing means for engaging with the straps.

30 40 45 THOMAS E. McMAHAN.
